CLAIM

The ornamental design for a two-wheeled vehicle and/or toy replica thereof, as shown and described.

DESCRIPTION

FIG. 1 is a perspective view of a two-wheeled vehicle and/or toy replica thereof showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view from another direction of the two-wheeled vehicle and/or toy replica thereof.

The broken lines are included for the purpose of illustrating portions of the article and form no part of the claimed design.

1 Claim, 8 Drawing Sheets
